UNITED STATES PATENT OFFICE.

WILLIAM THARBY, OF BUFFALO, NEW YORK, ASSIGNOR OF ONE-HALF TO
GEORGE GOETZ, OF BUFFALO, NEW YORK.

CUSHIONED HORSESHOE.

SPECIFICATION forming part of Letters Patent No. 713,716, dated November 18, 1902.

Application filed February 18, 1902. Serial No. 94,619. (No model.)

To all whom it may concern:

Be it known that I, WILLIAM THARBY, a citizen of the United States, residing at Buffalo, in the county of Erie and State of New York, have invented new and useful Improvements 5 in Cushioned Horseshoes, of which the following is a specification.

This invention relates to horseshoes having a cushioned tread-surface of soft rubber or 10 other suitable resilient material.

The object of my invention is to produce a shoe of this kind which is not liable to cause slipping by becoming clogged with snow and ice and in which the tread is backed or stiffened 15 in such a manner as to resist upward deflection of its central portion without, however, impairing its resilience.

In the accompanying drawings, Figure 1 is an inverted perspective view of the metallic 20 shell or frame of the horseshoe. Fig. 2 is a bottom plan view of the complete shoe. Fig. 3 is a longitudinal section of the same in line 25 3 3, Fig. 2. Fig. 4 is a transverse section in line 4 4, Fig. 2.

Like letters of reference refer to like parts 25 in the several figures.

The metallic shell or frame of the horseshoe has the general outlines of such a shoe and consists of a horizontal plate A, which is 30 comparatively thin and somewhat wider than that of an ordinary horseshoe and open in its center from toe to heel. This plate has a depending flange B, which extends completely around its outer margin and recedes from the 35 outer edge of the plate at the sides of the shoe to leave a narrow rim a for receiving the nail-holes a'. Openings a² may be formed in the plate A to reduce its weight. The heel portions of this plate are bounded at their 40 inner edges by depending flanges c of the same depth as the main flange B, which flanges form continuations of the main flange and extend to, or nearly to, the middle of the shoe. These inner flanges are curved to follow 45 the contour of said heel portions and form, with the outer flange B and the plate A, a shell or cavity adapted to receive a cushion D, of rubber or other suitable material. The plate A is provided at diametrically opposite 50 sides of its inner edge, preferably on the rear side of its transverse center line, with wings

or extensions e, which project inwardly into the approximately oval space inclosed by the plate. Each of these wings is provided at its rear edge with a depending flange e', which 55 is of the same depth as the adjacent flange c and forms the termination thereof. These terminal flanges are preferably arranged transversely of the horseshoe and form part of the front edge of the opening F, which receives the frog of the animal's hoof.

The rubber filling or cushion D is molded into the cavity of the metallic shell above described, the same entering the several openings of the plate A, which latter are preferably beveled, as shown in Figs. 1 and 3, to securely anchor the rubber therein without the use of separate fastenings.

The bottom of the pad, which forms the tread of the horseshoe, extends slightly below 70 the flanges B c e' and is formed with numerous ridges or otherwise suitably roughened, as shown, to prevent slipping. The rubber fills all of the openings of the metallic shell, excepting the frog-aperture F, and the portion of the pad which forms the front wall of this aperture is preferably arranged in line 75 with the transverse flanges e' to give the aperture an abrupt transverse edge, which readily cuts snow and ice, preventing the same from 80 packing in the aperture and forming a lump liable to cause slipping. The sides f of this aperture converge rearwardly to form a narrow throat or contraction f' and thence diverge to the heels of the shoe, as shown at f², 85 forming a rearwardly-flaring space between the heel portions of the shoe. By this peculiar formation of the frog-aperture the same closely fits the frog, preventing snow and ice from packing in the aperture. The best results are obtained by locating the front wall 90 of this aperture immediately in rear of the center line of the shoe, as shown.

By forming the metallic shell with a comparatively large central opening and arranging backing-wings e at opposite sides of this opening the cushion D is not backed so solidly as to destroy its resilience and yet is sufficiently stiffened at its central portion by said wings to prevent its being concaved or 100 pressed up out of place when the animal steps on a stone or other object. The flanges

e' at the rear edges of these wings confine the portion of the cushion in front of the frog-aperture F and prevent the same from encroaching upon the latter.

5 I claim as my invention—

1. A cushioned horseshoe, consisting of a plate of horseshoe form having a depending outer flange which extends around its outer margin, and depending inner flanges which extend along the inner margin of its heel portions and terminate near the middle of the shoe, and a pad or cushion bearing against the under side of said plate and confined between said inner and outer flanges, substantially as set forth.

15 2. A cushioned horseshoe, consisting of a plate of horseshoe form having a depending marginal flange and an unobstructed frog-opening, and provided at its inner margin on the front side of said opening with wings which extend inwardly beyond the edge of the opening, and a pad or cushion confined within said flange and bearing against the under side of said wings and constructed to clear said frog-opening, substantially as set forth.

25 3. A cushioned horseshoe, consisting of a plate of horseshoe form having a depending outer flange extending around its outer mar-

gin, wings projecting inwardly from the middle portion of its inner margin into the central opening of the plate, and depending inner flanges extending along its inner margin from the heels of the shoe to said wings and provided with transverse extensions which extend along the rear edges of the wings, and a pad or cushion applied to the under side of said flanged plate and confined between said inner and outer flanges, substantially as set forth.

30 4. A cushioned horseshoe, consisting of a plate of horseshoe form having a depending marginal flange, a main aperture in its front portion and a frog-aperture in its rear portion which latter aperture is flared at the heels of the shoe and contracted between said flared portion and its front portion, and a pad or cushion applied to the under side of said plate and filling the entire cavity thereof except said frog-aperture, substantially as set forth.

35 40 45 50 Witness my hand this 13th day of January, 1902.

WILLIAM THARBY.
